UNITED STATES PATENT OFFICE

99,425

DESIGN FOR A KETTLE

Emil R. Zettler, Deerfield, Ill., assignor to Revere
Copper and Brass Incorporated, Rome, N. Y., a
corporation of Maryland

Application February 12, 1935, Serial No. 55,368

Term of patent 7 years

To all whom it may concern:

Be it known that I, Emil R. Zettler, a citizen of the United States and a resident of Deerfield, county of Lake, State of Illinois, have invented a new, original, and ornamental Design for Kettles, of which the following is a specification, reference being had to the accompanying drawing, forming part thereof.

In the drawing:—

Fig. 1 is a top plan view of the kettle, showing my new design.

Fig. 2 is a side elevational view thereof.

I claim:—

The ornamental design for a kettle, substantially as shown.

EMIL R. ZETTLER.
